MATRIX BAND FORMING TEMPLATE
Frank J. Zolnowski, 3456 E. Plankinton Ave.,
Cudahy, Wis.

Filed Mar. 21, 1962, Ser. No. 181,286
7 Claims. (Cl. 33—174)

This invention relates to a template for forming matrix bands of the type which are looped around the tooth to be filled or restored and then tightened to closely conform to the irregular axial contour of the tooth.

Matrix bands of this general character are preferably curved lengthwise when the band is flat so that the band will become generally frusto-conical in shape when it is looped and drawn tightly around the tooth. Stated otherwise, the curved or generally arcuate shaped flat band will insure that the band will adapt itself snugly around the tooth at the gingival portion or gum line and then flare outwardly occlusally to facilitate proper restoration of the crown portion of the tooth.

Heretofore, bands of this type have been formed by cutting the band from a flat piece of steel matrix ribbon or the like to form a generally curved and flat band. This has proved to be not entirely satisfactory because the shape and size of the bands varied considerably with the skill of the dentist in cutting out the band. In other words, such bands often did not have the correct curvature that would result in a proper frusto-conical shape when looped around the tooth and which is necessary if the band is to adapt itself properly to the contour of the tooth. Generally stated, these bands would flare excessively in an occlusal direction and therefore be incapable of adapting themselves to the contour of the tooth at the crown portion. In other cases, these bands would not have sufficient taper when looped around a tooth to insure a snug fit around the gingival portion. Furthermore, these prior art bands would be either too narrow, that is of insufficient height, to entirely enclose the height of the cavity and thereby retain the matrix, or they would have too much height and thereby prevent proper and complete alignment between opposing teeth when the jaws of the patient were closed, as when a wax pattern for gold inlays was being formed in the cavity.

Bands of this general nature have also heretofore been formed from conventional steel matrix ribbon by simply folding a length of the ribbon over itself along a line inclined to the length of the ribbon, which would result in bands of generally arcuate or curved shape. This type of folded band has heretofore not been generally accepted because of the difficulty in forming it, and often requiring additional cutting with scissors in order to give it the proper general curvature. In other words, it has been difficult to consistently and accurately bend the ribbon over itself at the proper angle to thereby result in a properly curved band. When such a band was looped and tightly drawn around the tooth, an improper degree of flare and consequently an improperly fitting band resulted.

In addition, these folded type of bands were often unsatisfactory, because the resulting short height in the band which occurred in the center of the folded or double thickness portion of the band would not always be formed in the center of the length of the completed band. In other words, the center of the folded portion could not always and accurately be formed in the center of the length of the band. As a result, that portion of the folded band which was narrower in width than the remainder of the band could not be positioned in the center of the lingual side of the tooth where it is most desirable to locate it. Stated otherwise, the back or tongue side of the tooth is where less band height is ordinarily needed in order to completely and accurately confine the matrix, and it is

2

therefore desirable, when using a folded type of band, to position the narrow height portion of the band in the middle of that back or lingual side of the tooth.

Accordingly, the present invention relates to a template for forming a matrix band by folding the band over itself and into a flat and generally curved band. More specifically, the template provided by the present invention forms an accurately curved matrix band having a portion of less width located generally centrally of the length of the completed band. This portion of less width can thereby be positioned in the middle of the lingual surface of the tooth. Furthermore, the band formed by means of the present invention assumes the proper frusto-conical shape when tightened around the tooth to thereby result in a snug fit around the gingival portion of the tooth and a properly fitting occlusal portion around the crown portion of the tooth.

A more specific aspect of the present invention relates to a template of the above type which has measuring means for determining the proper length of ribbon to be cut from a stock roll in accordance with the type of tooth to be worked on and/or in accordance with the type of holder to be used to tighten and hold the band.

Furthermore, the invention contemplates that the template has indicia for properly positioning the ribbon on the template and in respect to a folding edge thereof; so that portion of least width of the folded band is located centrally of the length of the finished band.

More specifically, the present invention relates to a template of the above type having a folding edge over which the band is folded, and also having a guide edge which positions the band at the proper angle relative to the folding edge, so as to result in an accurately folded band of proper general curvature when flat.

Another more limited aspect of the invention relates to making the top edge of the template of a shape coinciding with the shape of the finished band, whereby a check may be made as to the correctness of the finished band.

Still another aspect of the invention relates to a template of the above type which also has a burnishing edge whereby the burnishing operation on the band being formed can be accomplished with the same template.

These and other objects and advantages of the invention will appear hereinafter as this disclosure progresses, reference being had to the accompanying drawings, in which:

FIGURE 1 is a general view of a template made in accordance with the present invention;

FIGURE 2 is a sectional view taken along line 2—2 in FIGURE 1, but on an enlarged scale;

FIGURE 3 is a view similar to FIGURE 1, but showing a band placed on the template and in position just prior to folding it over the top edge of the template;

FIGURE 4a is a side view of a folded band, on an enlarged scale, and before burnishing has been completed, and showing the template in the position and in the direction it is swingable or rockable for the preliminary burnishing operation, that is, for initially ironing or flattening the folded band;

FIGURE 4b is a view similar to FIGURE 4a, but showing the template used with a sliding movement across the band, as during the final burnishing operation, the template being held more or less normal to the band;

FIGURE 4 is a plan view of the band shown in FIGURES 4a and 4b but after it has been burnished;

FIGURE 5 is a perspective view of the band about to be placed around a tooth and in a "Wagner" type matrix holder;

FIGURE 6 is a plan view of the band around the tooth and showing the "Wagner" holder in the tightened position;

FIGURE 7 is an elevational view of the lingual side of

the tooth and taken generally along line 7—7 in FIGURE 6;

FIGURE 8 is a view similar to FIGURE 4, but showing a band foiled at an angle which is too acute to give the proper general curvature to the flat, folded band;

FIGURE 9 is an elevational view of a completed band formed from the FIGURE 8 band;

FIGURE 10 is a view also similar to FIGURE 4, but of a band folded at an angle which was too obtuse to result in a band of proper general curvature; and

FIGURE 11 is an elevational view of a completed band formed from the FIGURE 10 flat band.

The conventional steel matrix ribbons on the market today, and from which matrix bands are formed, are made in various widths, for example, $\frac{3}{16}$, $\frac{1}{4}$, $\frac{5}{16}$, $\frac{3}{8}$, and $\frac{7}{16}$ of an inch. These ribbons are on the order of .002 of an inch in thickness. Generally speaking, the most commonly used widths are the narrower ones mentioned and provide sufficient height to the completed frusto-conical band, in the great majority of cases, to retain the matrix in the tooth.

Portions of these ribbons are cut from the stock roll of the ribbon as needed, and it is desirable not to waste the ribbon by cutting off portions that are unnecessarily long or by making several improperly formed ribbons before a good one is finally fashioned.

The wider bands are used rather infrequently and for situations in which work must be done on the tooth below the normal gum line or in cases where certain portions of the band must be cut away to accommodate the gum, 30 other teeth, or other obstacles in the mouth.

The template made in accordance with the present invention provides a means for making bands with the most economical use of metal ribbon and limits the waste thereof to a minimum. Only enough ribbon material is cut from the stock roll to accommodate the type of tooth being worked on and the particular holder for holding the band. It will be appreciated that different types of holders are useable with the present invention, such as, for example, the Tofflemire holder shown in U.S. Patent No. 2,538,486, or the Wagner matrix holder of the type shown in this application. Generally speaking, the Wagner type of holder is preferable because it is considerably smaller and less obstructive and permits the patient to "bite" more easily during the tooth restoration process.

Referring more specifically to the drawings, the template T may be formed from a piece of sheet metal 1' or other suitable material and is shown as being generally rectangular in shape and preferably having the upper corners cut away for purposes that will appear herein-after, although other shapes may be used if desired.

Generally, there are two types of teeth with which the present apparatus may be used, namely, the bicuspid and the molar, and a matrix band of one particular length would be suitable for the molar of a small child and also suitable for the bicuspid of an adult. Similarly, a matrix band of one particular length would be useable for the molar of a child as well as for an adult's molar. Therefore, for the majority of widths of bands used, only two classifications of lengths are necessary, namely, a bicuspid length and a molar length.

Measuring Means

Referring again to FIGURE 1, the numeral B designates the general length from the righthand edge 1 of the template to which the ribbon should be cut if a bicuspid is to be worked on. Similarly, the reference numeral M inscribed near the lower edge of the template indicates the general length from the righthand edge 1 of the template to which a ribbon should be cut if a molar is to be worked on. These lengths are fairly accurate and average, assuming that the Wagner type of holder is to be used, and the length "B" for example may be approximately 42 millimeters, and the length "M" may be 54 millimeters.

If a holder is to be used which requires a longer band for gripping purposes, such as the Tofflemire holder previously referred to, then a length of ribbon of approximately 65 millimeters from the righthand edge 1 of the template to the indication marked X adjacent the lower edge of the template would be necessary, for either a molar or bicuspid.

As shown in FIGURE 1, the ribbon R has been placed along the measuring means prior to its being torn along edge 1. The matrix band MB so cut or torn along edge 1 is shown in FIGURE 3.

The rest of the bottom edge of the template may be also graduated into millimeter markings as indicated, in order that the doctor may have an additional convenient indication for measuring the length of ribbon desired for any particular use, in the event the main markings B, M, and X were not suitable.

Thus, the lower edge of the template forms a measuring means 2a along which the ribbon is laid before being cut and with the free end of the ribbon located at its proper reference point; the ribbon is then cut at the extreme right edge 1 of the template as by tearing it along the edge 1. Thus, a convenient measuring means is provided for cutting off a band MB from the stock roll of ribbon R with a minimum of waste.

Obviously, other measuring means may be provided on the template, and specific measuring marks as above indicated need not be employed. Instead, the template itself may be of such a length so as to serve as a measuring indication of the length of band to be cut from the stock roll. Experience may dictate to the user just what the length of band should be relative to the length of the template or markings thereon, for a given type of tooth or restoration.

Band Folding Edge

A folding edge 3 is provided along one side of the template, and it is over this edge that the band is tightly folded over. This edge should be straight and of a sufficient length to fully support the entire width of any size bands useable for this work.

Band Guide Means

Means are provided to properly position the straight band MB on the template and at the proper angle in respect to the folding edge 3 so that the flat band when folded over itself has the proper degree or amount of general curvature. As examples of folded bands of various general curvatures, a properly folded band is shown in FIGURE 4, a band having a fold that is too acute is shown in FIGURE 8, and a band that has a general curvature that is too flat is shown in FIGURE 10.

This means for insuring the proper angle of bend to the band, and consequently a proper general curvature, takes the form of a guide edge 4 which may comprise a straight strip of steel or other material that is welded or otherwise secured to the face of the template. This guide edge 4 forms an acute angle of approximately 19 degrees with the folding edge 3, and it has been found that this approximate angle provides a folded band of the most desirable general curvature for a matrix band.

As shown in FIGURE 4, the narrowmost portion 5 of the band is located in the doubled over portion thereof. It is important that this narrowmost portion is located approximately centrally of the length of the folded band, for reasons that will hereafter appear more fully. In order to insure that this narrowmost portion is so disposed relative to the length of the band, indicia b, m, and x are inscribed on the template and adjacent and along the guide edge 4. The small reference letters b, m, and x correspond to their capital letters counterparts B, M, and X located along the measuring means and are correlated therewith. If the dimensions for the lengths B, M, and X which were previously referred to are used, then the suitable dimensions for the distances from the small letters reference marks b, m and x along the guide

edge 4 and to the intersection of the folding edge 3 would be as follows. The distance from *b* to edge 3 should be approximately 30 millimeters; from *m* to edge 3 would be about 34 millimeters; and from mark *x* to edge 3 about 40 millimeters. With marks *B*, *M*, and *X* so correlated with marks *b*, *m*, and *x*, the folded area of the finished band will be located substantially centrally of the length thereof.

Assume that a biscuspid band MB has been cut by measuring from the righthand edge 1 of the template up to the mark *B*. That piece of band would then be placed tightly along the guide edge 4 so that one end of the band is in alignment with mark *b*, and the free end of the band extends beyond the folding edge 3.

Similarly, if a molar is to be restored, the *M* measuring mark would be used to determine the length of a band. In that case, reference *m* would also be used adjacent the guide edge 4 to axially position that particular band relative to the folding edge 3. The mark *X* on the measuring means is correlated with the mark *x* on the guide means for bands which are to be used with the Tofflemire type of holder mentioned in the above patent.

Thus, the indicia along the guide edge serves to axially position the band relative to the folding edge 3.

Fold and Burnishing the Band

Referring now to FIGURE 3, when the band MB has been positioned with one of its ends coincident with the mark *b*, the user tightly holds the band against the guide edge 4 and simultaneously rolls or folds the band tightly over the folding edge 3. This results generally in a folded band, as indicated in FIGURE 4a, with that portion of the band at the fold area being of double thickness.

The folded area is then compressed or burnished with any convenient hard tool or with the template itself as will be described, so as to reduce the overlapped area 5 to approximately only one thickness of metal as shown in FIGURE 4b. This insures that the band will wrap around the tooth without kinking or buckling to any appreciable extent.

The burnishing operation may be performed by the template itself by using the rounded lower edge 9 of the template, as indicated in FIGURES 4a and 4b. This rounded, burnishing edge of the tool is formed on the lower edges of the strip 2, the template itself, and another strip 10 which is welded or otherwise formed along the lower, rear side of the template.

As indicated in FIGURE 4a, the preliminary burnishing operation is accomplished by more or less rocking the template over the folded portion of the band and against any convenient hard surface, so as to substantially flatten the folded area. FIGURE 4b illustrates the final burnishing operation which consists of forcing the rounded edge down firmly on the band and then sliding the template back and forth over the folded area. This results in a band of practically uniform thickness throughout its length and one which bends uniformly around the tooth.

General

It should also be mentioned that the templates shown in the present application is satisfactorily used with the narrower types of ribbons above referred to, and if wider ribbons are to be used, a template having different measuring indicia thereon may be desired. It will be appreciated that the measuring indications along one edge of the template and the indicia along the guide edge may vary, for example with the width of band used, and the bands need not be cut exactly to length. Nevertheless, a correlation between the length of unfolded band and its position in respect to the folding edge 3 over which it is to be folded is important.

FIGURE 5 shows the band when its free ends have been inserted in the Wagner holder and when the adjusting nut 4' has been only preliminarily tightened to leave

the loop formed by the band sufficiently large to slip over the tooth T' to be worked on. The free ends of the band are held firmly in the holder by the sharp pins 4c and 4d which puncture the band ends. After the band is slipped around the tooth, the nut 4' is tightened additionally to draw the band ends further into the holder and tightly around the tooth, as shown in FIGURE 6.

As shown in FIGURE 7, the band MB formed on the present template results in a frusto-conical shape when looped around the tooth and which closely follows the axial contour of the tooth. The shape is such that the narrow end of the frusto-conical cone snugly fits around the gingival portion of the tooth, and the other end of the frusto-conical band widens occlusally to closely follow the contour of the crown portion of the tooth.

The position of the band on the tooth in regard to the height thereof is determined primarily by the type of work to be performed on the tooth. For example, for amalgam work, such as if a silver filling is to be placed in the cavity of the tooth, the band can be set rather high on the tooth, even higher than that shown in FIGURE 7, so long as the cavity portion thereof is completely confined by the band. Once the silver filling has been packed in the cavity and the band then removed, the filling can be sculptured to the exact contour of the tooth desired.

FIGURE 7 shows the top of the band positioned about level with the top of the tooth which is a desirable position for inlay work. For example, if a wax pattern is to be made of the cavity for a gold inlay, then the band would be positioned on the tooth as shown in FIGURE 7 to permit a functional bite to be taken prior to the carving.

For either of the above-mentioned type of tooth restoration work, the band provided by the present invention forms a desirably shaped frusto-conical band which closely follows the axial contour of the tooth and one in which the narrow portion 5 of the folded band is located on the lingual surface of the tooth where maximum band height is not necessary to insure confinement of the matrix.

FIGURE 8 illustrates a band that has been bent over itself at an angle which is too acute, thereby resulting in a frusto-conical shape having too much flare, as shown in FIGURE 9. This type of improperly formed band would result in escape of or excessive matrix at the crown portion of the tooth.

FIGURE 10 shows a band that has also been improperly formed because of too flat an angle of fold. This results in a frusto-conical cone (FIGURE 11) having sides that are too steep to permit the band to tightly abut against the gingival portion of the tooth, resulting in an escape of the matrix at this gingival portion.

Means are also provided on the template for checking the general curvature of the completed band so as to be sure it is correct. This means consists in removing the upper corners of the template so as to form the inclined edges 12 and 13. The three edges 3, 12, and 13 together form a pattern which the finished band should duplicate. Thus, when the band is finished, it is laid along on the back side 14 of the template and along the edges 3, 12, and 13 so that the upper edges of the band coincide with edges 3, 12, and 13. This forms a convenient, quick, and accurate means for checking the correctness of the general curvature of the finished band.

The distance between the guide edge 4 and the parallel edge 12 is preferably $\frac{5}{16}$ of an inch which will conveniently accommodate bands of up to $\frac{5}{16}$ of an inch, $\frac{5}{16}$ of an inch being the maximum average width used in the majority of situations.

The template provided by the present invention is flat and small in size which can be kept conveniently with other tools of the dentist, and provides an efficient and effective means for repeatedly, quickly, economically, and accurately forming matrix bands of ideal curvature.

Various modes of carrying out the invention are con-

templed as being within the scope of the following claims particularly pointing out and distinctly claiming the subject matter which is regarded as the invention.

I claim:

1. A matrix band forming template for guiding a band which is being folded over itself into a generally curved and flat band, said template being a generally flat and unitary member and having one side defining a folding edge over which said band is foldable, a guide edge formed on the template and arranged at substantially less than a forty-five degree angle with said folding edge and for guiding and positioning said band at the proper angle relative to said folding edge, and type of tooth indicia along said guide edge and spaced a predetermined distance from the intersection of said folding edge and said guide edge for determining the proper axial position of said band relative to said folding edge to thereby substantially center the finished fold on said band.

2. In a matrix band forming template for guiding a band while being folded over itself into a generally curved and flat band having a central folded portion, said template being a generally flat and unitary member, said template having means for measuring a band length, one side of said template defining a folding edge over which said band is foldable, a guide edge formed on the template and arranged at substantially less than a forty-five degree angle with said folding edge and for guiding and positioning said band at the proper angle relative to said folding edge type of tooth, and indicia along said guide edge and spaced a predetermined distance from the intersection of said folding edge and said guide edge for determining the proper axial position of said band relative to said folding edge, said measuring means being correlated with said indicia for a given length of band to thereby insure that said folded portion is located generally centrally of the length of the folded band.

3. A matrix band forming template for guiding a band while being folded over itself into a generally curved and flat band, said template being a generally flat and unitary member having one side comprising a folding edge over which said band is foldable, and a guide edge formed on said template and arranged at an acute angle of approximately 19 degrees with said folding edge for guiding and positioning said band at the proper angle relative to said folding edge.

4. A matrix band forming template for guiding a band which is being folded over itself into a generally curved and flat band, said template being a generally flat and unitary member having means for measuring a band length, one side of said template defining a folding edge over which said band is foldable, a guide edge formed on said template and arranged at an acute angle of approximately 19 degrees with said folding edge for guiding and positioning said band at the proper angle relative to said folding edge, and indicia along said guide edge for determining the proper axial position of said band relative to said folding edge.

5. In a matrix band forming template for guiding a band while being folded over itself into a generally curved and flat band having a central folded portion, said tem-

plate being a generally flat and unitary member having means for measuring a band length, one side of said template defining a folding edge over which said band is foldable, a guide edge formed on said template and arranged at an acute angle of approximately 19 degrees with said folding edge for guiding and positioning said band at the proper angle relative to said folding edge, and indicia along said guide edge for determining the proper axial position of said band relative to said folding edge, said measuring means being correlated with said indicia for a given length of band to thereby insure that said folded portion is located generally centrally of the length of the folded band.

6. A generally flat dental band forming template for guiding a steel matrix band while the latter is being folded over itself at an angle to its length and into a generally curved and flat band having a generally central folded portion, said template being a generally flat and unitary member having a generally flat front surface, said template also including means for measuring a length of steel matrix ribbon to be severed into band of definite length, a straight and thin folding edge along one side of said template and over which said severed band is foldable, a straight guide edge formed on said surface and arranged at an acute angle of generally 19 degrees with said folding edge, said band abuttable along said guide edge for being positioned at the proper angle relative to said folding edge for subsequent folding thereover, and indicia along said guide edge for determining the proper lengthwise position of said band relative to said folding edge.

7. A generally flat dental band forming template for guiding a steel matrix band while the latter is being folded over itself at an angle to its length and into a generally curved and flat band having a generally central folded portion, said template having a generally flat front surface and also including means for measuring a length of steel matrix ribbon to be severed into band of definite length, a straight and thin folding edge along one side of said template and over which said severed band is foldable, a straight guide edge on said surface and arranged at an acute angle of generally 19 degrees with said folding edge, said band abuttable along said guide edge for being positioned at the proper angle relative to said folding edge for subsequent folding thereover, and indicia along said guide edge for determining the proper lengthwise position of said band relative to said folding edge for determining the proper lengthwise position of said band relative to said folding edge, said measuring means being correlated with said indicia for a given length of band to thereby insure that said folded portion is located generally centrally of the length of the folded band.
